UNITED STATES PATENT OFFICE

2,536,947

ADJUSTABLE WINDOW VALANCE

Henry F. Lavorgna, Hyde Park, and Charles Leo Gately, Readville, Mass.

Application March 23, 1949, Serial No. 82,998

7 Claims. (Cl. 160—21)

1

This invention relates to drapery supporting devices and the like and has special reference to a window valance combination such as is used for producing an artistic effect at the top of window drapery, shades, blinds and the like.

In the construction of such valances for houses already constructed and not provided with built-in valances at the windows, it is necessary for a carpenter to measure the various windows at which valances are to be used and separately construct each valance and then nail or screw each one in place.

One important object of the present invention is to provide a novel valance combination with provision for adjustment in length to fit the window at which it is to be used.

Valance structures frequently have a front or face board carved or otherwise ornamented, and the ornamented feature frequently is of such character as to require centering in the window width for proper appearance.

Another object of the invention is to provide a novel combination of extensible valance wherein provision is made for permitting centering of the face board no matter to what length the valance may be adjusted. This combination is shown as comprising a face board and end supporting brackets within which there is provision for the endwise shifting of the face board to center the ornamental design.

In changing the drapery used in winter to that used in summer it sometimes occurs that light draperies of the summer type do not blend artistically with the valance which does present an artistic appearance with the heavier winter draperies.

A further object of the invention is to provide a novel form of extensible valance which may be taken down without the necessity of removing screws or nails and which may as readily be replaced or exchanged for another valance combination suitable in a change of window draperies.

With the above and other objects in view, the invention consists in general of certain novel details of construction and combinations of parts hereinafter fully described, illustrated in the accompanying drawing, and particularly claimed.

In the drawing:

Fig. 1 is an inside face view of a window showing the improved valance applied thereto.

Fig. 2 is an enlarged elevation, partly in section, showing the face board and certain end brackets as constructed in accordance with this invention.

2

Fig. 3 is a plan view of the arrangement shown in Fig. 2.

Fig. 4 is a still more enlarged view showing, in perspective, one of the brackets as used in Fig. 2.

Fig. 5 is a perspective view similar to Fig. 4 but showing a modified form of bracket.

Fig. 6 is a plan view showing the manner in which the invention may be used for triple windows.

Fig. 7 is a plan view showing the use of the invention for bay windows.

In each form of the invention as here shown there is provided a pair of complementary brackets 9, one being for the right hand side of a window, and the other for the left hand side of the window. These brackets may be made of metal, plastic, or other material.

Each of the brackets 9 includes an angular end plate 10 having vertical front and back edges.

20 A front plate 11 extends from the front edge of each plate at right angles thereto, one plate 11 extending to the right and the other to the left of the respective plate 10. A rearwardly projecting flange 12 extends from the lower edge of each plate 11 at right angles to the plate. The flange 12 is of uniform width throughout and a back plate 13 extends upwardly and is inclined inwardly from the rear edge of the flange 12. The back plate 13 has its upper edge curved 25 backwardly as at 14.

30 In the form of the invention shown in Figs. 1 to 4, inclusive, each plate 10 is provided adjacent its rear edge with vertically spaced inverted key-hole slots 15.

35 In the form of the invention shown in Figs. 5, 6, and 7 a flange 16 extends inwardly from the rear edge of the plate 10 and in this flange there are provided vertically spaced inverted key-hole slots 17.

40 In connection with the plates 10 there are provided supports 18 which extend inwardly at right angles to plates 10 and are preferably semi-circular in cross-section with their concaved side facing inwardly so that drapery rods indicated in broken lines at R may be supported thereby. Connecting the front plates 11 and supported by the flanges 12 is a valance board 19 which is gripped by the upper portions of the back plates 13 while the curved portions 14 45 guide the board 19 into position.

The flanges 12 sustain the weight of the valance boards 19 which are supplied in lengths substantially shorter (e. g. one inch) than the width of the window to be equipped with this novel combination end brackets 9 and ornamental valance

55

boards 19. This board 19 is supplied of such thickness as to be gripped frictionally between the back plates 13 and front plates 11, the back plates thus acting as clamping springs for the end portions of the boards 19 which, as above stated, are supplied in lengths somewhat shorter than the widths of standard windows. This permits stores to stock this valance combination equipment, consisting of the end brackets and scrolled boards, for home application to windows of approximately the same widths and the purchaser will be able to center the valance board correctly within the faces 11, 12, and 13 of the brackets, due to the length of the supporting surfaces 12 relative to the length of the valance board. As here shown, the ornamental feature of the valance board 19 includes a scrolled lower edge 20. It will be obvious from the drawing that the center of the scroll can be adjusted endwise between the brackets when they are in place on the window frame by a simple sliding movement.

In erecting the device, screws S having shanks of such diameter that they may pass into the smaller ends of the keyhole slots but having heads which will not pass through the smaller ends but will pass through the larger ends of the slots, are chosen. These screws are screwed into the ends or face of the lintel L according to the form of bracket used and are spaced to suit the spacing of the key-hole slots. The brackets are then positioned so that the screw heads will pass through the slots and the brackets are then drawn downwardly which holds them removably in place. The valance board is then applied and adjusted as above described.

It is to be noted that the brackets each has a pocket open at the top and one side as formed by the front plate 11 with its bottom flange 12 and back plate 13.

What is claimed is:

1. In a window valance, an elongated face plate, and a pair of supporting brackets spaced apart at the top and sides of a window frame, each of which slidably engages one end of the face plate, each bracket comprising a right angular plate having a front and an end extending rearwardly from the outer edge thereof and disposed vertically on edge to cover the ends of the face plate, means at the bottom of the front to support and grip the back of the face, and means to attach the end to the frame.

2. In a window valance, an elongated face plate, and a pair of brackets each having a pocket open at the top and one side wherein one end of the face plate slidably fits, said brackets comprising short right angular plates closed at the front and outer side, said front having a rearwardly extending bottom flange to support the face plate on edge at its end portions and an upturned flange at the rear edge of the bottom flange to clamp the face plate against the front inwardly of the outer side, and means at the back of the outer side to detachably secure the same to a window frame.

3. In a window valance, a single elongated face plate, and a pair of unitary end brackets each having a front plate provided at its lower edge with a rearwardly extending flange whereon one end of the face plate rests, each bracket also having a back plate rising from the rear edge of said flange and holding the said face plate end against the front plate.

4. In a window valance, an elongated face plate, and a pair of brackets each having a front

plate provided at its lower edge with a rearwardly extending flange whereon one end of the face plate rests, each bracket also having a back plate rising from the rear edge of said flange and holding the said face plate end against the front plate, said rear plate being inclined towards the front plate, said rear plate being inclined towards the front plate and forming resilient means to hold said face plate end frictionally in place, said brackets concealing the ends of the face plate therein.

5. In a window valance, an elongated face plate in combination with a pair of brackets each including a vertical end plate, a front plate extending inwardly at a right angle to the forward edge of the end plate, a flange extending rearwardly from the bottom edge of the front plate, and a back plate extending upwardly from the rear edge of said flange and inclined toward the front plate, said end plate being provided adjacent its rear edge with vertically spaced inverted key-hole slots, said face plate having its ends resting on the flanges of the front plate and gripped between the front and rear plates.

6. In a window valance, an elongated face plate in combination with a pair of brackets each including a right angular end plate, including an outer plate, a front plate extending at a right angle to the forward edge of the outer plate, a flange extending rearwardly from the bottom edge of the front plate, and a back plate extending upwardly from the rear edge of said flange and inclined toward the front plate and its upper portion curved backwardly, said outer plate being provided at its rear edge with a flange projecting at a right angle, said last mentioned flange being provided with vertically spaced inverted key-hole slots, said face plate having its ends resting on the flanges of the front plate between the front and rear plates and concealed thereby.

7. In a window valance, an elongated face plate in combination with a pair of brackets each including a right angular end plate, including an outer plate, a front plate extending at a right angle to the forward edge of the outer plate, a flange extending rearwardly from the bottom edge of the front plate, and a back plate extending upwardly from the rear edge of said flange and inclined toward the front plate and its upper portion curved backwardly, said outer plate being provided adjacent its rear edge with support-engaging means, said face plate having its ends resting on the flanges of the front plates between the front and rear plates and bridging the space between the brackets, and concealed at its end portions and shiftable endwise to center the face plate.
